UNITED STATES PATENT OFFICE.

JESSE BERRY, OF LISBON, IOWA.

SELF-BINDING HARVESTER.

1,179,997.

Specification of Letters Patent. Patented Apr. 18, 1916.

Application filed August 17, 1914. Serial No. 857,253.

To all whom it may concern:

Be it known that I, JESSE BERRY, a citizen of the United States, residing at Lisbon, in the county of Linn and State of Iowa, have invented certain new and useful Improvements in Self-Binding Harvesters; and I do hereby declare the following to be a full, clear, and exact description of the invention, such as will enable others skilled in the art to which it appertains to make and use the same.

This invention relates to self-binding harvesters, and its object is to facilitate the discharge of the bound sheaf by shifting the position of the shoe, with which the knotter is connected, to give an enlarged space for the sheaf as so discharged from the binder.

The nature of the invention is fully disclosed in the description and claims following, reference being had to the accompanying drawings, in which—

Figure 1 is an elevation of a device embodying my invention as seen from the right side. Fig. 2 is a central, sectional view of the same as in discharging position and seen from the opposite side. Fig. 3 is a plan view of the same.

In the drawing, 1 designates the inclined table on which the gavel is collected and bound, and is provided with the usual packer 2, holding foot 3, and needle 4. The knotter 5 is indicated, without being shown in detail, and is driven by the interrupted gear 6 on the shaft 7, which, it will be understood, is connected operatively with a self-binding harvester not shown. In the revolution of the shaft 7 the sheaf 9 is discharged from its bound position between the table 1 and the shoe 10, which shoe, as heretofore mounted, has been connected rigidly with a supporting rod (usually tubular) 11. The sheaf has therefore been gathered, packed, bound and discharged between two rigid and substantially parallel surfaces, the top of the table and the under side of the shoe. In practice the construction described demands considerable power, over that normally employed, in the ejection of the sheaf, since the sheaf must be forced, by a quick motion, out between two practically parallel surfaces. This is of course especially true in the case of large, heavy and closely fitting sheaves or bundles. My invention is designed to relieve the binder of much of this extra power, and make the operation of the

binder easier on the driving mechanism of the machine and easier for the team.

Referring again to the drawings, it will be seen that the shoe is not connected rigidly to any support at its front end, but is mounted so as to rock on the drive-shaft 7, and when its front end is depressed, as shown in Fig. 2, the space between it and the table opens out rearwardly, thus relieving the top and bottom pressure on the bundle, and permitting it to be easily discharged. The support for the shoe is a suspending rod 12 passing through a pivoted arm 13 and a superimposed spring 14. The arm is mounted pivotally on the rod 11, and at its free end engages a cam 15 on the interrupted gear wheel 6. This cam is so timed that on the completion of the knotting operation, and after the needle has commenced to retreat, the arm descends and the shoe tilts as above described to permit the easy ejection of the bundle by the discharge arms 16. The shoe is held laterally at the front end by the guide-lugs 17 of a collar 18 secured to the rod 11. A collar 19 holds the arm 13 in place adjacent.

It is of course essential to the proper working and safety of the machine that all the operations be positive and accurately timed. For example, it would not do for the shoe to be depressed while the needle is making its forward thrust (outward, as regards the machine), nor during the operation of the knotter. If all the parts are accurately formed and set, however, the device will perform its functions properly with only the mechanism above described. But as a protection against possible emergencies a supplemental positioning device is provided. This consists of foot 20 pivoted in the upper part or neck of the shoe, and means for controlling its swinging movement. Its forward movement, considered with respect to the needle, is limited by side lugs 21 which in the forward position abut against the neck of the shoe. It is given a positive backward movement by the very act of depressing the shoe, a simple device for that purpose being a finger 22, which, when the shoe is depressed, engages the guide-collar and swings the foot back, as shown in Fig. 2. Its backward movement is not wholly dependent upon the movement of the shoe, however, but may anticipate and control such movement of the shoe. This

will be apparent by considering the needle to be in its extreme position, as indicated by the dotted lines in Fig. 1. If now the cam and its connections, owing to wear, or otherwise, should not support the shoe at the proper height, the foot, resting on the curved upper arc of the needle, will do so. Under such conditions the least retreating motion of the needle will tilt the foot, and the shoe will descend, continuing its descent by gravity as soon as the toe of the foot passes the center of gravity drawn vertically through the foot-pivot.

In order to attain the highest efficiency the shoe should be made considerably lighter than those in general use, which are rather heavy castings. This will be clear when it is considered that the knotting and ejecting operations are very quickly performed, and the drop of the shoe should be sudden to correspond. Being sudden, it is desirable, to avoid jar and strain, that the weight of the descending parts be not excessive. In practice, therefore, I prefer a skeleton shoe, 25 the main portion of which is a fork of steel formed substantially like the part numbered 10^a, having a looped and upturned neck to receive the pivoted foot, and twisted and spread out at the other extremity, with the knotter casting 10^b riveted thereto. The side fenders of the shoe may be simple steel rods 10^c set in lugs 23 of the guide-collar 18, and held suitably in place, as by set-screws 25. The fenders need not tilt, and the lower portion of the shoe, which bears against the bundle, is both strong and light.

Having thus described my invention, I claim:

1. In a self-binder, the combination with a rotating knotter-shaft, a knotter in intermittent operative relation therewith, and a needle in coöperative relation to the knotter, of a cam carried by said shaft and a connection of the same with said shoe whereby the shoe is intermittently tilted, and a swinging foot mounted at the free end of the shoe and above the path of the needle, substantially as and for the purpose set forth.
2. In a self-binder, the combination with

a rotating knotter-shaft, a knotter in intermittent operative relation therewith, and a needle in coöperative relation to the knotter, of a shoe mounted to oscillate on said shaft, means for intermittently oscillating the same, a swinging foot mounted at the free end of the shoe and above the path of the needle, and adapted to rest on the needle when thrust forward, and limit the tilt of the shoe, and means connected with said foot adapted to positively shift it out of such supporting position as the needle retreats and the shoe descends to normal position.

3. In a self-binder, the combination with a rotating knotter-shaft, an intermittently operating knotter mounted thereon, and a needle coöperating with said knotter, of a shoe mounted to rock a limited distance on the knotter-shaft, a lateral guide for its free end, and means adapted to tilt the shoe to bundle-relieving position during the discharge of the bundle, and to restore it to normal position prior to the forward thrust of the needle.

4. In a self-binder, the combination with a rotary knotter-shaft, an intermittently operating knotter mounted thereon and a needle coöperating with the knotter, of a shoe composed of flat bar-steel and a knotter casting to which it is attached, the bar forming a loop at the free end, twisted and upturned, and a swinging foot pivoted therein.

5. In a self-binder, the combination with a rotary knotter-shaft, an intermittently operating knotter mounted thereon and a needle coöperating with the knotter, of a shoe mounted to rock on the knotter-shaft and adjacent stationary rods fixed to some rigid portion of the machine, substantially parallel with the shoe and at the sides thereof, and adapted to shield the shoe from straw and litter, substantially as described.

In testimony whereof I affix my signature in presence of two witnesses.

JESSE BERRY.
